UNITED STATES PATENT OFFICE.

ARTHUR F. O'CONNOR, OF CHICAGO, ILLINOIS, ASSIGNOR TO THE UNION RAILWAY EQUIPMENT CO., OF CHICAGO, ILLINOIS, A CORPORATION OF SOUTH DAKOTA.

VENTILATOR.

1,339,973.

Specification of Letters Patent.

Patented May 11, 1920.

Application filed December 11, 1917. Serial No. 206,650.

To all whom it may concern:

Be it known that I, ARTHUR F. O'CONNOR, a citizen of the United States, and resident of Chicago, county of Cook, and State of Illinois, have invented certain new and useful Improvements in Ventilators, of which the following is a specification, and which are illustrated in the accompanying drawings, forming a part thereof.

10 The invention relates to ventilators, and more particularly ventilators for fruit cars and the like.

The object of the invention is to provide a simple, strong, weather-tight ventilator which can be readily opened from the outside of the car and held in either open or closed position as desired.

One embodiment of the invention is illustrated in the accompanying drawings, in 20 which—

Figure 1 is an elevation of a car end having the improved ventilator attached thereto;

25 Fig. 2 is an elevation of the car end from the inside;

Fig. 3 is a front view, on an enlarged scale, of a portion of the ventilator showing the means for operating the ventilator from the outside of the car;

30 Fig. 4 is a section on the line 4—4 of Fig. 3;

Fig. 5 is a section on the line 5—5 of Fig. 3;

Fig. 6 is a perspective view of one of the 35 shutters of the ventilator;

Fig. 7 is a detail view of a modified form of locking device for holding the ventilator closed or open; and

Fig. 8 is a section on the line 8—8 of 40 Fig. 3.

The ventilator comprises a frame 10 which is mounted in the frame of the car, such as end plate 11, end posts 12, and belt rail 13. Laterally projecting lugs 14 are arranged on this frame to extend over the sheathing of the car, through which attaching bolts or the like may be passed for securing the frame to the car structure.

In this frame 10 are pivotally mounted 50 two parallel rows of shutters 15, adapted to open and close. The construction of the individual shutters is shown more particularly in Fig. 6. Each shutter 15 may be made of cast metal, preferably malleable iron, with

projecting trunnions 16 at each end adapted 55 to be journaled in corresponding apertures in the frame 10 of the ventilator. The trunnions 16 are located adjacent the lower edge of the shutters so that gravity will hold the shutters open. At their inner ends each shutter is provided with an inwardly extending flange 17 for connecting the shutters to an operating link 18 by means of pins 19. The link 18 is arranged between the two rows of shutters, and the pins 19 extend through the 60 inwardly projecting flanges 17 on the shutters of both rows, as shown in Fig. 2. Upward movement of the link will, therefore, close the shutters, and downward movement of the link will open them. 70

In order to open and close the ventilator from the outside, and to hold it in either its open or closed position, the link is provided with a pair of laterally projecting arms 20, 21. These arms are adapted to extend 75 through the slots 22, 23, in the frame 10. The upper arm 20 is formed with an aperture 24 through which the operator's fingers may be inserted to get a firm grip thereof for opening and closing the ventilator. The 80 arm 21 is provided with means for locking the ventilator in either its open or closed position. For this purpose outwardly projecting flanges 25 are arranged on the frame on either side of the arm 21. In these 85 flanges 25 are formed a pair of holes 26, through which a pin 27 may be passed and secured by means of a car seal 38. The arm 21 has a similar hole 28, adapted to register with either the upper or lower of each pair 90 of holes 26, according as the ventilator is opened or closed.

As there may be considerable play between the pins 19 and the link 18 and other parts of the ventilator, provision is preferably made for closing the ventilator more tightly than is ordinarily possible by means of the pin 27. In the construction shown this is accomplished by providing a notch 30 in the upper part of the arm 20 for the 100 reception of a dog 31 slidably mounted in a frame. The arm 20 in closing the ventilator moves not only upwardly, but also outwardly, so that the extent to which the dog 31 can enter the notch 30 depends upon 105 the amount the arm 20 is raised. The dog 31 has, therefore, a wedging action in the notch 30, which prevents the arm 20 from

moving inward and consequently prevents the link from falling and opening the ventilator.

When it is desired to open the ventilator the dog may be moved out of engagement with the notch 30 by means of its outwardly projecting arm 32. In order to allow the ventilator to be tightly closed even after wear has occurred, sufficient play is preferably allowed between the pin 27 and the apertures 26 or 28 to enable the arm 20 to be raised as far as the shutters 15 will allow, and be locked in that position by the dog 31, while the pin 27 is in engagement with the hole 28 and upper holes 26. The 15 with the hole 28 and upper holes 26. The two locking devices, *i. e.*, the pin 27 and dog 31, are therefore supplementary to each other. When the ventilator is open it will be held in that position by gravity, 20 or if it is desired to use a more positive means for holding the ventilator open the pin 27 may be passed through the lower holes 26.

Instead of providing the notch 30 with a smooth inclined edge for engagement with the dog 31, this edge may be shown with a series of steps formed therein (as shown in Fig. 7) which correspond with different extents of opening of the ventilator.

As it is important that the ventilator be constructed so as to exclude the weather, a flange 29 is provided along the lower edge of each shutter, this flange being offset to an amount equal to the thickness of the shutter so that it can overlap and bear against the upper edge of the shutter adjacent thereto.

As rain or the like may pass through the slots 22, 23, in the frame, a shield 33 of galvanized iron, or other material, may be provided which has apertures through which the arms 20, 21, extend. This shield, therefore, hangs freely on the arms 20, 21, and is kept in place by lateral guides 40 (Fig. 8) attached to the frame 10, so that the arms 20 and 21 slide relatively to the shield as the ventilator is opened or closed. As water may run down this shield on the inside of the frame, a catch pin 34 is arranged between the frame 10 and the belt rail 13 into which the water drips. This pan has an upwardly turned inner edge 35 and a downwardly turned outer edge 36. Transverse channels 37 are formed on the under side of the frame 10 for allowing the water to escape from the pan 34.

The shutters are preferably arranged, as shown, in two rows, with their operating mechanism between to prevent undue strain on the shutters and to place a more even strain on the link and arm by which they are opened and closed. The shutters 15 have flanges 41 extending between the trunnions 16, as shown in Fig. 6, to stiffen the 65 shutters. Flanges are used instead of a

thickened part, of the same diameter as the trunnions in order that all parts of the shutter may be of substantially the same thickness and therefore cool in casting at the same rate.

I claim as my invention—

1. A ventilator comprising, in combination, a series of shutters, each shutter mounted to swing about a pivot adjacent its lower edge, a lug projecting inwardly from the lower portion of each shutter, a link connecting said lugs whereby said shutters tend to open by gravity, an arm on said link projecting to the outside of the ventilator and means for holding the arm in adjusted position.

2. A ventilator comprising, in combination, a frame, a series of shutters pivotally mounted therein, a link pivotally connected to each of said shutters on the inner side of the ventilator, an operating handle on the outer side of the ventilator, a connection between said handle and said link, and means for locking said handle in a plurality of positions relatively to said frame.

3. A ventilator comprising, in combination, a frame, a series of shutters pivotally mounted on said frame adjacent their lower edges, a link pivotally connected to each of said shutters on the inner side of the ventilator, an arm on said link projecting through the outer face of said frame, and a locking member adapted to engage a shoulder on said arm, the point of engagement of said member and said shoulder depending upon the distance said arm projects beyond the outer face of said frame.

4. A ventilator comprising, in combination, a frame, a series of shutters pivotally mounted on said frame, a link pivotally connected to each of said shutters on the inner side of the ventilator, an arm on said link projecting through the outer face of said frame, and a locking member adapted to engage a shoulder on said arm, the point of engagement of said member and said shoulder depending upon the distance said arm projects beyond the outer face of said frame.

5. A ventilator comprising, in combination, a frame, a plurality of shutters, pivotally mounted in the frame and each having a lug projecting backwardly, a link bar pivotally attached to the several lugs and having an arm projecting through the frame, the upper face of the arm being notched, and a detent slidably secured to the outer face of the frame for entering the notch.

6. A ventilator comprising, in combination, a frame, a plurality of shutters pivotally mounted in the frame and each having a lug projecting backwardly, a link bar pivotally attached to the several lugs and having an arm projecting through the frame, the upper face of the arm being notched,

the outer margin of the notch being inclined inwardly and downwardly, and a detent slidably secured to the outer face of the frame for entering the notch.

- 5 7. A ventilator comprising, in combination, a frame having a transverse apertured bar, two sets of shutter plates each plate being pivoted in a side member and the transverse bar of the frame and having at its inner end a lateral arm, a link bar back of the transverse bar pivotally attached to each arm, and an arm projecting from the link bar through the transverse bar whereby the shutters may be controlled.
- 10

8. A ventilator comprising, in combination, a frame having a transverse apertured bar, two sets of shutter plates each plate being pivoted in a side member and the transverse bar of the frame and having at its inner end a lateral arm, a link bar back of the transverse bar pivotally attached to each arm, an arm projecting from the link bar through the transverse bar whereby the shutters may be controlled, such arm having a cam face at its upper margin, and a slide 25 plate carried by the transverse bar for coöperating with the cam.

ARTHUR F. O'CONNOR.
